CONVERTIBLE CAR.

APPLICATION FILED NOV. 20, 1906.

2 SHEETS—SHEET 2.

THE NORRIS PETERS CO., WASHINGTON, D.C.

UNITED STATES PATENT OFFICE.

JOHN A. BRILL, OF PHILADELPHIA, PENNSYLVANIA.

CONVERTIBLE CAR.

No. 852,767.

Specification of Letters Patent.

Patented May 7, 1907.

Application filed November 20, 1906. Serial No. 344,190.

To all whom it may concern:

Be it known that I, JOHN A. BRILL, a citizen of the United States, and a resident of the city and county of Philadelphia and State 5 of Pennsylvania, have invented certain new and useful Improvements in Convertible Cars, of which the following is a specification.

My invention relates to convertible cars wherein movable side panels are provided 10 which are adapted to pass below the plane of the car floor, and in which there is a step provided extending within the lateral limits of the car as defined by the stanchions. As in such constructions, there will be a space be- 15 tween the car floor or sill when the panel of the latter is lowered, I have provided a novel filler to close the space when the panel is lowered, which filler is carried by the panel, and operates itself to close the space as the 20 panel is lowered, so that no attention need be given to the filler.

My present invention is an improvement on a portion of the device shown in my application serially numbered 323,439 and filed 25 the 26th day of June, 1906.

In the drawings forming part of this application Figure 1 is a perspective view of a portion of a car showing my improvements applied thereto. Fig. 2 is a section through a 30 portion thereof showing the panel in its lowest position. Fig. 3 is a section on line 3—3 of Fig. 2, looking in the direction of the arrows. Fig. 4 is a section of the parts shown in Fig. 2, showing the operation of the filler as the panel is lowered. Fig. 5 is a perspective view of one end of the filler. Fig. 6 is a perspective view of a portion of the panel. Fig. 7 is a perspective view showing a modification of the end of the filler. Fig. 8 is a 35 plan view of Fig. 11, showing the application of the modified structure. Fig. 9 is a section taken on the line 9—9 of Fig. 13. Fig. 10 is a sectional view showing the action of the filler as the panel is being lowered. Fig. 11 is a cross-section showing the position of the filler when the panel is lowered. Fig. 12 is a 40 similar view showing the action of the filler as the panel is being lowered. Fig. 13 is a similar view showing how the filler rests 45 against panel as the latter is being raised. Fig. 14 is a section showing the invention in its broader aspect, and Fig. 15 is a perspec-

tive view of the end of the modified form of filler.

In cars of this construction, the side sill is 55 formed of angle metal so as to provide a longitudinal and a vertical web; the longitudinal web forming a step for the car extending within the lateral limits of the car as defined by the stanchions. Various forms of such 60 cars have been constructed, to which my improvements may be applied, but in the one herein illustrated for the purpose of showing the application of my invention, the car sill consists of a lower web 1 extending longitudinally, and a vertical web 2 at right angles to the former. If desired, the wooden filler 3 is secured to the vertical web 2. Above the web 2 and the filler 3, there is provided a suitable flooring 4. The stanchions 5 are 70 secured upon the web 1, preferably by means of metal pockets 6, so that they find their support upon the web 1 and are also secured to the web 2 by means of bolts 7 which pass through the metal pockets, through the stanchion ends and the web 2; the stanchions are provided with vertical grooves 8, which are continued by grooves 9 in the metal pockets, so that the panel 10 may be lowered to a 75 point below the plane of the car floor. 80

In the form herein illustrated, the panel 10 is adapted to pass down and rest upon the sill web 1; when so lowered there is a space between the panel and the car floor, which for many reasons should be closed when the 85 car is used as a closed car. For that reason I have provided a filler for closing the space which, in this present invention, is secured to the panel itself and moves therewith, so that as the panel is stored in the roof pocket, or 90 other suitable storing place, the filler will be carried with it. Another feature of my invention is that as the panel is lowered to its lowermost position, the filler is so constructed that it will, of itself, return to a longitudinal position and properly close the space 95 from the panel to the floor and between the stanchions.

In Figs. 1 to 6 inclusive, the filler consists of a flat plate 11 which is curved slightly upwardly at 11^a, and it is secured to the panel by means of a hinge connection so that it may be turned from a vertical position 100 against the panel to a substantially horizon-

tal position. Means for securing the plate to the panel, as herein constructed, consists of ears 12 at the end of the plate which are flush with the ends thereof and are offset and provided with apertures 13. There is one at each end of the plate 11, and on the panel there are secured extending ears 14 having apertures 15 which are adapted to aline with the apertures 13. The ears 14 are secured to the panels by screws 16 or other suitable means, and are sufficiently distant from each other to straddle the ears 12 and be flush with the edge of the panel. Suitable pins 17 are secured to the ears 12 and 14, so as to 15 form a hinge on which the plate 11 moves. On the opposing faces of the stanchions, and preferably on the pocket forming a component part of the stanchions, I provide a projection which will contact with the plate 20 11 as the panel is lowered and which will cause the plate to swing into a horizontal position as the panel reaches its lowermost position. The projection 18, which is secured against the face of the metal pocket 6 by 25 means of bolts 19, which secures the projection to the web 2 and against the metal pocket is provided with a circular upper surface 20, and a similar circular recess 21. As the panel is lowered, as shown in Fig. 4, the 30 curved edge 11^a of the plate contacts with the point 22 of the extension and the plate slides upon the curved surface 20 as the panel moves, and the plate 11 swinging on its hinge will finally assume a horizontal position between the panel and the car floor. The purpose of the recess 21 is to receive the 35 ear 14 on the panel.

By referring to Figs. 7 to 15, the modified construction of the end plate will be fully understood; in this form the plate is provided 40 at its end with a vertical web 23 from which projects a horizontal extension 24 parallel with plate 11, substantially Z-shaped in cross-section. In this case there is a small 45 projection 25 provided on the face of the post which will engage the projection 24 as the panel is lowered, so that it will rock on the projection 25 and cause the plate 11 to assume a horizontal position, as shown in 50 Fig. 11. Except for this extension, the plate and the construction is otherwise the same.

I believe I am the first to provide a movable side panel with a plate adapted to close the space between the panel and the car floor 55 when the panel is lowered, particularly in providing such an extension which will be self-operative.

Having described my invention, what I claim is:

60 1. A car having a floor, stanchions, and movable panels beyond the floor limits, and a filler for the space between the panel and floor, carried by the panel.

2. A car having a floor, stanchions, and movable side panels beyond the floor limits, 65 and a filler for the space between the panel and floor, said filler being hinged to said panel.

3. A car having a floor, stanchions and movable panels beyond the floor limits, and a 70 filler for the space between the panel and floor, carried by the panel, and means for engaging the filler when lowered to form a support therefor.

4. A car having a floor, stanchions and 75 movable panels beyond the floor limits, and a filler for the space between the panel and floor, said filler being secured to and carried by the panel and adapted to lie vertically near the panel when the latter is raised, and 80 to be turned horizontally when the panel is lowered.

5. A car having a floor, stanchions and 85 movable panels beyond the floor limits, and a filler for the space between the panel and floor, said filler being secured to and carried by the panel and adapted to lie vertically, and means whereby the lowering of the panel will cause the filler to assume a horizontal 90 position.

6. A car having a floor, stanchions and a 95 movable panel beyond the floor limits, a filler carried by the panel and adapted to lie vertically, and projections on the opposing faces of the stanchions adapted to engage the filler and turn it to a horizontal position.

7. A car having a floor, stanchions and a movable panel, beyond the floor limits, a filler carried by the panel and adapted to lie vertically, and projections on the posts having 100 concave upper surfaces on which the filler engages and by which it is turned to a horizontal position.

8. A convertible car having a floor, stanchions, and side steps extending within the 105 lateral limits of the car as defined by the stanchions, a movable side panel extending below the plane of the floor and a filler carried by the panel and adapted to close the opening between the panel and floor.

9. A convertible car having a floor, stanchions, and side steps extending within the 110 lateral limits of the car as defined by the stanchions, a movable panel between the stanchions, extending below the plane of the floor and a filler hinged to the panel and adapted to be moved horizontally, and means on the stanchions for engaging the filler and causing it to move to a horizontal position as the panel is lowered.

10. A convertible car having a floor, stanchions and side steps extending within the 115 lateral limits of the car, a movable panel between the stanchions, and a filler hinged to the panel and composed of a plate, and an 120 offset projection 24, and means on the stan-

chion for engaging the projection 24 to cause the plate to move to a horizontal position.

11. A convertible car having a floor, stanchions and side steps within the lateral limits of the car, a movable panel between the stanchions and a filler hinged to the panel and composed of a plate 11, and a web 24, the plane of the web and plate being directed to-

ward a common meeting point, and means on the stanchion for engaging the web 24.

Signed this 7th day of November, 1906.

JOHN A. BRILL.
